PHILIPPE PAILLE, OF ST. JAMES PARISH, LOUISIANA.

Letters Patent No. 85,955, dated January 19, 1869.

IMPROVEMENT IN MACHINES FOR DEFECATING AND BLEACHING CANE-JUICE.

The Schedule referred to in these Letters Patent and making part of the same.

To all whom it may concern:

Be it known that I, PHILIPPE PAILLE, of the parish of St. James, and State of Louisiana, have invented a certain new and useful Improvement in Machines for Defecating or Bleaching Cane-Juice; and I do hereby declare the following to be a full, clear, and exact description of the same, reference being had to the annexed drawings, making a part of this specification, on which, at

Figure 1, is presented a perspective, and at

Figure 2, a sectional view, the bisection being vertical and central.

It is well known that the use of sulphurous-acid gas for defecating and bleaching cane-juice and other saccharine liquids, with the view of improving the sugar to be made therefrom, has, to a greater or less extent, long obtained in all sugar-producing countries in which the arts of civilization have been introduced, and that a great variety of mechanical organisms and arrangements have been devised, and are now in common use, that have for their special object the injection, infusion, and distribution of this gas in and through the cane-juice or other liquid that is to be purified and bleached, in order that the sugar into which it is to be subsequently converted, or, more accurately speaking, which is to be extracted from it, shall be of light color, or perfectly white.

It is also very familiar knowledge that most, if not all of the so-called defecating-machines that are used in connection with saccharine liquids, thus far invented, violently stir, agitate, or dash about the same, by means of some mechanical appliance or other, to which rapid positive motion is given, to secure the thorough permeation of the liquid by the gas, and the consequent contact of all portions of the former with the gas, that is necessary to effect the desired ends; and that such agitation very greatly impairs the granulating-capacity of the liquid, as well as the quality of the sugar produced therefrom, by preventing the perfect crystallization thereof. In truth, the beating and violent agitation of the cane-juice, which are incident to the use of nearly every existing popular machine, in the process of defecation, is one, if not the principal cause, of the disproportionate yield of molasses from a given quantity of the juice, as compared with the sugar obtained therefrom, which so frequently annoys and puzzles the manufacturer, if it does not subject him to actual loss.

The object of my invention is to effect the impregnation of the juice with the gas, and a general and perfect diffusion of the latter throughout every part of the former, without violent agitation of the same, or the employment of any mechanical instrumentalities for such purpose, and thus to avoid the evil consequences to which I have referred, and at the same time to secure quicker and better results, and at less cost than can be attained by existing machines, or the methods now practised; and

My invention consists of an arrangement of a pecu-

liarly-constructed gas-forcing pump, or of several of the same, within a receiver in which the juice and the sulphur-fumes, to produce the desired chemical effect, are both contained, in such a manner that, by the combined agency of the pump and the superior levity of said fumes, which cause them to rise to the surface of the juice when injected or forced into it, a thorough infusion and diffusion of the gas is secured throughout every part of the juice.

But my invention will be better understood by referring to the drawing, on which A marks the juice-receiver, the juice flowing into it directly from the pressure-rollers of the mill, through any proper conduit-pipe or trough. This receiver may be of any dimensions, and constructed of wood or metal, or a combination of both. It may also be of any other form than that shown on the drawing, which convenience or fancy may dictate.

The juice enters the receiver A near its top, we may suppose through a pipe, a, and is discharged through a slightly larger pipe, b, a little below the induction-pipe a, and on the opposite side of the receiver. The object of having the eduction a little larger than the induction-pipe is to prevent the juice from rising above the former.

The fumes or gas is brought into the receiver from the sulphur-furnace, through a pipe, c, which, entering at the bottom thereof, as shown, extends a little way above the pipe a, and is provided at its top with a valve, d, hinged so as to articulate upwardly, and allow the gas to flow out of the pipe c.

Over this vertical section of the pipe c is placed a hollow plunger or sleeve, e, which, by means of proper links, is operated by a crank in the same manner as the plunger of an ordinary forcing-pump. The bottom of the plunger-sleeve e must move in its up-and-down reciprocating operation from a point very near the bottom of the receiver A to a point a few inches below the discharge-pipe b. The diameter of the plunger-sleeve e should be at least twice as great as that of the pipe c, in order to afford a considerable concentric open space around the latter, for the downward passage of the gas under the forcing action of said sleeve in its downward movement. This sleeve e is air-tight, except at its bottom, where it is open, and for a few inches above its bottom, where it is perforated on its sides with small holes, as shown:

The gas, after having performed its office, escapes through the pipe f, which, in order that the gas may be, in some degree, packed in the receiver, ought to be somewhat smaller than the pipe c. This object, however, may be accomplished just as well by the introduction of a blower in the pipe c.

The top of the receiver should be so securely attached, that it will afford a steady support for the plunger-sleeve e, which necessarily must pass through it, a proper stuffing-box being provided, to prevent leakage.

The operation of my invention is as follows, to wit:

As soon as the juice begins to flow into the receiver A, the sulphur-furnace is put in action, and the gas flows therefrom into the vertical section of the pipe, c, that is within the receiver, and through the valve d, at the top thereof, into the plunger-sleeve e, which, by its action, when in operation, forces the same down around the pipe c, to the bottom of the receiver, where it escapes through the perforations in the sleeve, in radiating and powerful currents, that diffuse it throughout every part of the juice, at and near the bottom of the receiver.

In this diffused state, the gas, by reason of its great relative buoyancy, instantly rises to the surface of the juice, and, in doing so, comes necessarily in contact with every part and particle of the same, and the defecation and bleaching thereof are completely accomplished, without, it will be perceived, subjecting it to more agitation than is produced by the passing of the gas through it, which, it is obvious, cannot be in the slightest degree injurious.

In the downward motion or stroke of the plunger-

sleeve, the valve d is closed by the pressure of the gas above it, which cannot therefore go back into pipe e.

Like the receiver, the plunger-sleeve and pipe e, or such part of it as is within the receiver, may be made of metal or wood, and either square or round.

Having thus described my invention, and explained its mode of operation,

What I claim, and desire to secure by Letters Patent, is—

The arrangement of one or more plunger-sleeves, e, within a cane-juice or other saccharine-liquid defecating and bleaching-receiver A, and in connection with a vertical section or sections of a gas-pipe or pipes c, when these several parts are constructed, united, and operate substantially as herein described, for the purpose set forth.

PHILIPPE PAILLE.
